UNITED STATES PATENT OFFICE.

ROBERT PORTER, OF OTTUMWA, IOWA.

HARNESS-BUCKLE.

SPECIFICATION forming part of Letters Patent No. 282,366, dated July 31, 1883.

Application filed January 15, 1883. (No model.)

To all whom it may concern:

Be it known that I, ROBERT PORTER, of Ottumwa, in the county of Wapello and State of Iowa, have invented a new and useful Improvement 5 in Harness and other Buckles, which improvement is fully set forth in following specification.

This invention, though applicable to other purposes, has reference more particularly to 10 buckles for connecting the hame-tug with the front end of the trace in harness for horses; and it has for its object to produce a neat and light buckle wherein the tongue of the buckle is relieved of part of the strain.

15 The invention consist in the special new construction of the buckle.

The accompanying drawings, which form a part of this specification, represent buckles constructed in accordance with the invention 20 or with parts thereof.

Figure 1 is a plan of one of the improved buckles with hame-tug and trace in position; Fig. 2, a section of the same; Figs. 3 and 4, perspective views of the parts separated; Fig. 25 5, a perspective of a modified form of the bail or draft-loop, and Figs. 6 and 7 views similar to Figs. 1 and 2 of another style of buckle.

A is the frame of the buckle, and B the sliding bail or draft-loop, to which the hame-tug 30 C is fastened. D is the trace, and E the tongue of the buckle. The buckle-frame comprises the side bars *a b*, the front cross-bar *c*, center bar, *d*, and rear cross-bar *e*. It is provided with the breeching-loop *f*, back-band loop *g*, 35 and belly-band loop *h*, (one, two, or all,) or it is unprovided therewith, as may be desired.

The bail or draft-loop B comprises the side bars *i*, front cross-bar *k*, rear cross-bar *l*, lugs *m*, and flanges *n*. The side bars *a b* of the buckle-frame, as shown, incline away from each other toward the front of the buckle, so as to give space for the bail or draft-loop between them. The front cross-bar *c* is therefore longer than the rear bar *e*, and the frame 40 has the general shape of a trapezoid. This is the preferable shape. The lugs *m* are continuations of the rear cross-bar *k* of the bail. They rest upon the side bars *a b* of the frame. The said side bars are curved or dished slightly 45 in the middle, so that in drawing forward the lugs *m* will travel up an incline plane. The

amount of the curvature or dishing and the size of the cross-bar *k* and lugs *m* are such that the trace *D*, which is passed under the cross-bar *e*, over the bar *k*, and under the bar *c*, will 55 be bent outward over said bar *k* between the others. This is an important feature of the invention, since the bend over the cross-bar *k* is less likely to permit slipping than a simple clamping between it and the bar *c*. In 60 drawing forward, the inclined side bars, by forcing said cross-bar *k* outward, cause quite a sharp bend to be made. This bending of the trace may be relied upon, with the aid of the tongue, to hold fast the trace; but it is preferred to clamp it also. It is for this purpose 65 that the flanges *n* are provided in front of the cross-bar *k*. They clamp the trace against the cross-bar *c*. The inner surface of the latter is preferably shaped to conform to the outer surface of said flanges, both being curved. Thus 70 an even bearing over a comparatively large surface is secured. In Fig. 5 the flanges *n* are omitted. The side bars *i* of the bail or draft-loop are curved outward (*i. e.*, toward the top 75 in Fig. 2) behind the front cross-bar *l*, so as to receive the trace between them. They are preferably also so shaped that when the bail or draft-loop is drawn forward the hame-tug, which surrounds the front cross-bar *l*, will 80 press the trace outward, and thus make it fit snugly against the front bar of the buckle-frame. The tongue *E*, as shown in Figs. 1 and 3, is attached to the front cross-bar *c* of the buckle-frame, being made in one piece therewith. In Figs. 6 and 7 the tongue *r*, which corresponds to the tongue *E*, is attached to a separate tongue-piece, *F*, which rests at the ends upon the side bars *a b*, and which is made broad in the middle, so as to have a large 85 bearing upon the trace. In Figs. 6 and 7 the rear cross-bar *k* of the bail or draft-loop is provided with a tongue, *G*. This tongue may be omitted or may be used, as desired. The central cross-bar, *d*, strengthens the buckle-frame; but the main object in its use is to prevent the bail or draft-loop from dropping through the frame accidentally. It is desirable for the buckle to have a length somewhat greater than its width. If, therefore, the space 90 between the front and rear cross-bars of the frame were left open, it would be very easy for

the bail or draft-loop to turn, and then there would be nothing to sustain it. The central cross-bar, by shortening the space, prevents this undesirable result from happening. It is 5 so placed that the space for the bail is large enough for it to be inserted when the trace is not in place and small enough to prevent its turning or removal when the trace has been introduced.

10. Modifications besides those indicated can be made without departing from the spirit of the invention, and portions of the invention may be used separately. For example, the tongue might be placed upon the rear cross-bar of the buckle-frame; but this would bring 15 strain upon the side bars, which is not desirable, and would necessitate the making of them and of the rear cross-bar heavier than would otherwise be necessary. The central cross-bar 20 might be omitted and other changes could be made.

The trapezoidal buckle-frame might be used with other styles of bail or draft-loop, and the bail described with buckle-frames not trapezoidal.

25. Of course, buckles for other purposes could be made in accordance with the invention.

The separate tongue-piece F, Figs. 6 and 7, could be provided with lugs on the bottom to 30 fit between the side bars *ab*.

For the purpose of this invention, the two 35 forms of buckle are considered as substantially alike; but that shown in Figs. 6 and 7 contains improvements not found in the other buckle, and as these improvements are not specifically claimed herein, the right is reserved of making them the subject of separate application.

Having now fully described my said invention and the manner of carrying the same into effect, what I claim is—

1. In a buckle, the combination of a buckle-frame having cross-bars and dished side bars with a draft-loop having front and rear cross-bars, and side bars and lugs at the end of and in line with the rear cross-bar, the said lugs 45 resting upon the side bars of the buckle-frame, and the dishing of said side bars being less than the thickness of the said rear cross-bar, so that the trace or strap will, by said rear cross-bar, be bent outward between the cross-bars of the buckle-frame, substantially as described.

2. In combination with a buckle-frame having cross-bars of unequal length connected by side bars, a bail or draft-loop having cross-bars connected by side bars, which fit between the more widely separated ends of the side bars of the buckle-frame, and are curved outwardly so as to receive a trace or strap between them, said bail or loop being also provided with lugs which rest upon the side bars of the buckle-frame, substantially as described.

3. The bail or draft-loop having a rear cross-bar and lugs at the ends thereof, and provided with internal flanges in one piece with said rear cross-bar, in combination with a buckle-frame, substantially as described.

In testimony whereof I have signed this specification in the presence of two subscribing witnesses.

ROBERT PORTER.
